UNITED STATES PATENT OFFICE

111,796

DESIGN FOR A FIGURE TOY

Edward S. Savage, Rochester, N. Y.

Application July 6, 1938, Serial No. 78,308

Term of patent 7 years

To all whom it may concern:

Be it known that I, Edward S. Savage, a citizen of the United States, residing at Rochester, in the county of Monroe and State of New York, have invented a new, original, and ornamental Design for a Figure Toy, of which the following is a specification, reference being had to the accompanying drawing, forming a part thereof.

In the drawing:

Fig. 1 is a plan view of a figure toy showing my new design; Fig. 2 is a side perspective view thereof.

The dominant feature of my design consists in the body portion and legs substantially as shown in full lines in the accompanying drawing.

I claim:

The ornamental design for a figure toy, substantially as shown and described.

EDWARD S. SAVAGE.
